(57) **CLAIM**

The ornamental design for a pair of chair armrests, as shown.

DESCRIPTION

The Invention is a pair of chair armrests specifically designed for folding director's chairs.

FIG. 1 is a perspective view of my new design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The broken lines showing in FIG. 1 are for environmental structure only and form no part of the claimed design.
